PRESSURIZED SPRAY DISPENSER HEAD

James M. Berry, 202 Fisher Park Circle, Greensboro, N.C.

Filed Jan. 19, 1962, Ser. No. 68,376

Term of patent 14 years

(Cl. D58—26)

FIG. 1

FIG. 4

FIG. 2

FIG. 3

FIG. 5

FIGURE 1 is a top plan view of a pressurized spray dispenser head, embodying my new design.

FIGURE 2 is a side elevational view thereof.

FIGURE 3 is a front elevational view thereof.

FIGURE 4 is a rear elevational view thereof.

FIGURE 5 is a bottom plan view thereof.

I claim:

The ornamental design for a pressurized spray dispenser head, as shown.
